UNITED STATES PATENT OFFICE.

PATRICK B. DELANY, OF SOUTH ORANGE, NEW JERSEY.

ELECTRO-MAGNETIC INSTRUMENT.

SPECIFICATION forming part of Letters Patent No. 426,247, dated April 22, 1890.

Application filed January 30, 1890. Serial No. 338,564. (No model.)

To all whom it may concern:

Be it known that I, PATRICK B. DELANY, a citizen of the United States, residing at South Orange, State of New Jersey, have invented 5 certain new and useful Improvements in Electro-Magnetic Instruments, of which the following is a specification.

The invention is applicable to all such instruments in which an armature having a 10 tractable or biasing spring is attracted by a magnet; but the invention is more especially designed for use with telegraphic relays. The telegraph-operator must frequently adjust the spring of his relay armature-lever to 15 compensate for varying conditions of the battery or circuit, and in adjusting the spring to increase its tension he is liable, through carelessness, to overstrain the spring, and even to wind it upon the rotating pin or post by 20 which it is adjusted.

My invention is designed to prevent the possibility of such accidents, which impair the efficiency of the springs and frequently render them useless. 25 Another feature of my invention comprehends the idea of preventing the total relaxation of the spring—that is, providing for the minimum tension below which the spring cannot be adjusted. In either case when the limit 30 of adjustment by the manipulation of the spring has been reached further adjustment must be effected by the adjustment of the electro-magnet itself.

In the accompanying drawings, Figure 1 is 35 a side elevation; Fig. 2, an end view of a device for limiting the adjustment of the spring, and Figs. 3 and 4 are detail views of modified ways of limiting the adjustments of the spring.

40 A represents an ordinary adjustable electro-magnet; B, its armature; C, the retractile spring of the armature; D, the cord leading from the end of the armature-spring to the rotating post E, having a thumb-wheel e and 45 mounted in the sliding or adjustable arm F supported in a post G. This is the ordinary construction, and is well known.

The cord D passes through a guide Y, preferably having an elongated vertical opening 50 for the passage of the cord. The overstraining of the spring is prevented by providing

the cord with a device that will abut against the guide Y and prevent further movement of the cord through it. A simple and convenient way of effecting this is to form a knot 55 *d* in the cord between the end of the spring and the guide Y. As this knot cannot pass through the opening in the guide Y the operator cannot strain the spring beyond the point where the knot strikes the guide. It is 60 therefore impossible to injure the spring, and of course it is never possible in a thoughtless moment to wind the spring upon the rotating post E. When the limit of adjustment has been reached, a further adjustment may be 65 effected in the ordinary way by the adjustment of the magnet away from the armature.

In Fig. 3 I have shown another manner of accomplishing the desired result. In this case the cord *c*, need not pass through a guide Y, 70 the limitation of the adjustment of the spring being effected in the following manner: A light cord *c*, passing centrally through the spring, is connected with each of its ends and is sufficiently slack to allow the spring to be 75 drawn out to the desired limit. In some classes of instruments, however, it is desirable that the tension of the spring upon the armature shall never be reduced below a certain point, and for this purpose a knot *c'* may be 80 tied in the spring between the guide Y and the rotating post.

In Fig. 4 the overstraining of the spring is prevented by a wire *x*, formed with hooked ends and lying loosely within the spring. Ob- 85 viously, when the ends of the spring are drawn against the hook on each end of the wire it cannot further be extended. Of course the details of construction of a stop device for limiting the adjustment of the spring may 90 be varied. The arrangements shown, however, are practical ones, and serve to illustrate the invention.

I am aware that, broadly, devices have been arranged to prevent the overstraining of spiral springs and do not claim such subject-matter, but limit my claim to the specific combinations below recited.

I claim as my invention—
1. The combination, with an electro-magnet, 100 its vibrating armature-lever, the armature-lever spring, and means for gradually adjust-

ing the spring, of a stop for limiting the straining of the spring.

2. The combination, with an electro-magnet, its armature-lever, the spring of the armature-lever, and means for gradually adjusting the spring, of a stop for limiting the reduction of tension upon the spring.

3. The combination of an electro-magnet, its armature-lever, the armature-lever spring, the means for gradually adjusting the spring, and stops for limiting the adjustment of the spring in both directions.

4. The combination of an electro-magnet, its armature-lever, means for adjusting the magnet toward and from the armature-lever, the armature-lever spring, means for gradually adjusting the spring, and a stop for limiting the straining of the spring. 15

In testimony whereof I have hereunto subscribed my name.

PATRICK B. DELANY.
